UNITED STATES PATENT OFFICE.

GEORGE G. HENDERSON, DECEASED, LATE OF SEWICKLEY, PENNSYLVANIA; BY MARY P. HENDERSON, EXECUTRIX, OF SEWICKLEY, PENNSYLVANIA.

WIRE-SHAPING APPARATUS.

Application filed June 24, 1926. Serial No. 118,264.

The invention relates to apparatus for shaping wire and finds practical application in shaping from wire forms or frames for stretching stockings.

5 In the accompanying drawings Fig. I is a view in plan of a machine in which the invention is embodied. Figs. II and III are views to larger scale, Fig. II in vertical and longitudinal section and Fig. III in plan 10 of a portion of the machine. Figs. I and III show certain moving parts in alternate extreme positions of movement. Fig. IV is a fragmentary view in vertical and transverse section, on the plane indicated at IV— 15 IV, Fig. III. Fig. V is a view in elevation of the article produced by the machine in its operation.

With attention upon Fig. V it will be understood that the stocking form or frame 20 consists of a loop of wire of proper shape and size to be introduced within a freshly washed and still damp stocking and to sustain the stocking in distended condition and so to prevent shrinkage during drying. It 25 is desirable that this loop at its outer end be broken or divided, as indicated at *a*, in order that it may be collapsed for insertion within a stocking; and ordinarily the length of 30 wire shaped as shown in Fig. V is at one end provided with a rigidly borne ferrule, into which, after the form has been introduced within a stocking, the opposite end may be sprung, that the form may continue 35 in expanded condition, to serve its intended purpose. The form as it is shown in Fig. V lacks such a ferrule; for the ferrule forms no part of the present invention, and for present purposes the disclosure is clearer in the showing of the form so far incomplete 40 as to lack the ferrule alluded to. It is however important to remark that in the bending of the wire to the shape shown in Fig. V the opposite ends must be turned to axial alignment, and the means for effecting precisely that shaping of the wire involve invention, as hereinafter set forth.

In Fig. III will be found a set of wire bending dies. These consist of block 1 and jaws 2 and 3. The block 1 is of such shape 50 and size that a length of wire may be crushed upon its periphery to constitute the article of Fig. V. The jaws 2 and 3 are mounted alternately to open and to close upon block 1, and by so closing to crush a 55 length of wire as described. Fig. III shows

the jaws open; Fig. I shows them closed. Additional jaws 4 and 5 move toward and from and cooperate with block 1 at its opposite ends, to perform particular functions presently to be described.

60

A horizontally extending plate 6 reciprocates horizontally in ways 7 which engage its opposite parallel edges, and reciprocation is imparted from a rotating crank shaft 8 through a connecting rod 9. Shaft 8 may 65 be rotated in any suitable manner, and in Fig. I means for rotating by hand are, by way of example, indicated.

The block 1 is rigidly mounted upon slide 6; it extends horizontally; it is spaced at a 70 convenient height above the upper surface of slide 6; and slide 6 is conveniently recessed immediately beneath block 1, as indicated at 60, that the articles as they are formed may be delivered from the machine 75 by gravity.

The block 1, it will be remarked, is non-symmetrical; its opposite sides, as it is seen in place upon the slide 6, are unlike; and the jaws 2 and 3 which engage it are correspondingly unlike in the configuration of their work-engaging faces. With this characteristic in mind, it will be remarked of block 1 that it is arranged approximately upon 80 but only approximately upon the mid-line of 85 the structure, and that the axis of the leg portion of block 1 extends approximately but not precisely in parallelism with the line of sliding movement. The departures from the precise position here indicated are made 90 intentionally, to the end that the crushing strains which shape the wire shall be distributed most effectively throughout the length of the wire.

Jaws 2 and 3 are pivoted in slide 6 on a 95 common pivot, adjacent the toe end of block 1. Adjacent their remote ends these jaws are pivoted to arms 20 and 30 which in turn are pivoted to the plates which constitute ways 7. The pivoting to the ways 7 is effected through blocks 70 which are bolted to but adjustable in their positions upon ways 7, to the end that when the parts have been assembled, minute adjustment may be made in limiting the range of relative movement of operating parts and in varying and distributing the intensity of the crushing strains. The working faces of jaws 2 and 3 correspond in shape to the opposite sides 105 of block 1. The jaws may be provided with 110

ledges 21, 22, and 31, for sustaining a newly introduced wire in position for operation.

Comparison of Figs. I and III will serve to illustrate the general mode of operation. The slide 6 reciprocates between these two extreme positions and in so doing alternately closes the jaws 2 and 3 upon the block 1 and opens them again. When the jaws are in the open position shown in Fig. III a straight and accurately cut length *w* of wire is fed horizontally and transversely between block 1 and the open jaws 2 and 3. It may be accurately positioned by abutment at one end upon a stop 71 set on one of the ways 7, and when brought to position it may be left sustained in position, resting upon the ledges 21, 22, and 31. This initial position is indicated in Fig. III. Left-to-right movement of slide 6 then brings the parts to the positions shown in Fig. I, in which the jaws 2 and 3 have closed upon the sides of block 1 and in so doing have crushed the length of wire between the meeting faces and have strained it beyond its limit of elasticity and have given it permanent set in the shape so imposed upon it. In further operation the jaws swing away from engagement upon block 1 and in so doing release the wire now shaped to the desired form, and the article then eases away from block 1 sufficiently and falls by gravity through the opening 60 in plate 6.

It will be observed that, in order to have free discharge of the finished article downward, and indeed to have full and free compression of jaw 2 upon block 1, the ledge 22 must stand away from block 1 at an interval, and I provide means for clamping the infed wire *w* at its middle part, while still at its ends the wire rests on ledges 21 and 31. This clamp is the jaw 4, already mentioned. It is mounted upon slide 6 and is itself adapted to slide within a limited range longitudinally upon the slide 6. Normally it is held remote from cooperation with block 1, that is to the right, Figs. I, II, and III, by the tension of a spring 40. From such retracted position the clamp 4 is advanced to clamp the length of wire to the tip end of block 1 by the thrust of a cam disk 90, in which the connecting rod 9 conveniently terminates and by which it is pivoted to slide 6. The cam disk is so particularly shaped that in the course of revolution of shaft 8 the point of engagement of the spring-backed jaw 4 upon the cam disk 90 advances from the surface 91 of less radius to the surface 92 of maximum radius. As this point of engagement advances to the surface of maximum radius, it will be perceived that jaw 4 will be advanced against spring tension toward block 1. The particular proportions are such that, beginning with the parts in the position shown in Fig. III, the jaw 4 moves

forward to clamp the length of wire *w* at its mid-part against the tip of block 1 just after slide 6 begins its left-to-right movement; and it continues in such advanced position until the maximum squeeze is past, that is until the slide comes approximately to the position shown in Fig. I. It then promptly recedes and allows the then finished article to escape.

Allusion has just been made to the fact that the slide 6 advances from left to right to and beyond the point where the crushing strain is at a maximum. This will be understood on considering Fig. I, in which the slide 6 is shown at the limit of its left to right stroke; and when in that position it will be observed of the arms 20 and 30 that they have swung to and slightly beyond a position of alignment; and by as much as they have passed beyond a position of alignment, the crushing strain with which they compress the wire upon the edges of block 1 is eased.

Mention has been made of the necessity of bringing the ends of the wire in the finished article to axial alignment. The laterally swinging jaws 2 and 3 are incapable of exerting pressure properly directed to accomplish this. But in the further advance of slide 6 beyond the point where arms 20 and 30 are in alignment, and at a moment when in the operation of the machine the other wire-shaping strains are relaxed, the jaw 5 advances and cooperating with the remote end, the left-hand end of block 1, shapes the two ends of the wire upon it; so that in the finished article the two ends are axially aligned.

Jaw 5 is mounted for longitudinal reciprocation upon slide 6, as will be clearly apparent on comparing Figs. II, III, and IV. A lever 50 pivoted in brackets which depend from the under-side of slide 6 engages jaw 5. A stop 51, rigidly borne upon a fixed support, as upon a bridge member 72 between ways 7, but minutely adjustable in its position, is arranged in the path of advance of the power arm of lever 50, as it is borne by the slide 6. The minute position of stop 51 is such that, as the slide 6 advances beyond the point of maximum strain imparted by jaws 2 and 3, the swinging of lever 50 by abutment of stop 51 causes jaw 5 to advance, and, engaging the ends of the wire, to crush them upon the end of block 1. At that moment in the operation the crushing strains of jaws 2 and 3 are, as has been said, somewhat eased and accordingly the wire is more freely responsive to the strains exerted upon it by jaw 5. In such manner the ends of the wire are shaped to axial alignment.

As slide 6 makes its right-to-left stroke, jaw 4 having already receded, jaw 5 begins to recede, then in turn jaws 2 and 3 recede. The shaped article then eases somewhat

from the close contact into which it was crushed upon the face of block 1. In consequence of such recession the article loosens and falls away, and as the parts come again to the position shown in Fig. III, the machine is ready to receive a fresh length *w* of wire.

Invention is claimed as follows:

1. In apparatus for shaping wire the combination of a block, two oppositely moving jaws adapted to advance and to bend a length of wire around and to crush it upon opposite faces of the block and to recede from the block, means to operate aforesaid jaws, said means constructed and arranged to ease the crushing pressure of the aforesaid jaws upon the block before receding movement begins, and a jaw operating in sequence when the aforesaid oppositely moving jaws have eased their crushing pressure on the block, adapted to engage the ends of a length of wire brought to adjacent positions by the operation of the pair of jaws first named and to shape the engaged ends upon the block.

2. In apparatus for shaping wire the combination of a pair of arms rotatable upon fixed pivots, a block reciprocable between said arms, a pair of jaws pivoted at one end each to one of said arms and at the other end to a pivot having fixed position relatively to said block, and adapted as the block recip-

rocates to close upon said block from opposite sides, the said arms in the range of block reciprocation coming to and passing beyond alignment, and a jaw closing upon said block as the block passes beyond the position in which said arms are in alignment.

3. In apparatus for shaping a length of wire to the form of a loop with ends adjacent and in axial alignment one with another, the combination of a pair of fixed pivots, a pair of arms swinging on said pivots, a slide reciprocable between said pivots, a forming block borne by said slide, a pair of forming jaws pivoted each at one end to said slide and at the other end to one of said arms, the said slide being reciprocable to and beyond a point where said jaws close from opposite sides upon said form with said swinging arms in alignment, a jaw adapted to close upon said block at one end while the pair of jaws first named continues open and adapted to open as said slide passes beyond the position above mentioned with said swinging arms in alignment, and a fourth jaw adapted to close upon said block at the opposite end as the said slide passes beyond the said position of alignment of the swinging arms.

In testimony whereof I have hereunto set my hand.

MARY P. HENDERSON,
Executrix of George G. Henderson, deceased.
